CLAIM

The ornamental design for a vehicle wheel front face, as shown and described.

DESCRIPTION

FIG. 1 is a front perspective view of the vehicle wheel front face showing my design;

FIG. 2 is a front elevation view thereof; and,

FIG. 3 is a left side elevation view thereof.

The broken lines are for the purpose of illustrating portions of the vehicle wheel front face and form no part of the claimed design.

1 Claim, 3 Drawing Sheets# US D1,093,260 S
